UNITED STATES PATENT OFFICE.

DAVID S. WILLIAMS, OF PHILADELPHIA, PENNSYLVANIA.

DESIGN FOR A LAMP-HOOD.

SPECIFICATION forming part of Design No. 32,165, dated January 30, 1900.

Application filed December 23, 1899. Serial No. 741,473. Term of patent 7 years.

To all whom it may concern:

Be it known that I, DAVID S. WILLIAMS, a citizen of the United States of America, and a resident of No. 903 Walnut street, in the city 5 and county of Philadelphia, State of Pennsylvania, have invented a new and original Design for a Lamp-Hood, of which the following is a specification.

My invention relates to a new and original 10 design for a hood for petroleum incandescent lamps, and is more particularly adapted to that class of lamps producing a light of high candle-power with an incandescent mantle by the use of kerosene-oil vapor under con- 15 siderable pressure.

Referring to the accompanying drawings, forming part of this specification, Figure 1 illustrates a perspective of the hood, showing my new design, and Fig. 2 represents a plan 20 view of the same.

As illustrated in the drawings, the leading or material feature of my design consists of a disk A, provided at the top with a rectangular box or casing A', provided with openings a and a' to receive a vaporizing-tube, and a 25 cylindrical box or casing B adjacent to one of said openings to receive the mouth of the mixing tube or chamber of a petroleum incandescent lamp.

Having described my invention, what I 30 claim as new, and desire to secure by Letters Patent, is—

The design for a hood, substantially as herein shown and described.

Signed by me at Philadelphia, Pennsylvania, this 21st day of December, 1899.

DAVID S. WILLIAMS.
